BY Chas. E. Journeay

ATTORNEY.

UNITED STATES PATENT OFFICE.

WILLIAM P. GREGORY, OF STONE CANON, CALIFORNIA.

SIGNAL SYSTEM.

1,408,190.

Specification of Letters Patent. Patented Feb. 28, 1922.

Application filed July 13, 1921. Serial No. 484,284.

To all whom it may concern:

Be it known that I, WILLIAM P. GREGORY, a citizen of the United States, residing at Stone Canon, in the county of Monterey and State of California, have invented new and useful Improvements in Signal Systems, of which the following is a specification.

This invention relates to a signal system and particularly pertains to a means adapted to be used in connection with railway block signal systems. It is common practice at the present time to install block signal systems along railway rights of way, these systems being designed to give a warning signal when a block of the track is in clear. The present arrangement, however, does not provide positive means whereby danger along a bridge, trestle, or other similar structure would be indicated, and it is the principal object of the present invention to provide means readily incorporated within the present block signal system whereby danger along a bridge or trestle may be positively indicated, even though the rails remain intact.

The present invention further contemplates a fusible joint for signal wires, which joint embodies the use of a minimum amount of metal between the terminals of the joint, thereby tending to decrease the resistance to the flow of electric current through the wires, as is at present common.

The present invention contemplates the use of a loop of wire, the terminals of which are secured to opposite sides of a break in a railway track, and which loop is carried across a bridge or trestle, or like structure, and returns to the same side of the structure from which it was started, said loop being made up of a plurality of wires connected by fusible joints, which joints would be affected by an objectionable temperature and would cause the wires to be separated and the flow of current interrupted.

The invention is illustrated by way of example in the accompanying drawings in which—

Fig. 1 is a view in plan showing a simple application of the present invention;

Fig. 2 is a view in transverse section and elevation through a bridge or trestle;

Fig. 3 is an enlarged view in section and elevation showing a fragmentary portion of the wire used.

Referring more particularly to the drawings, 10 and 11 indicate the rails of a rail-

way right of way. These rails are interrupted by joints at intervals throughout their length, and in the present case the joints are insulated, as indicated at 12. As will be understood, the rails carry the current of a block signal system and when interrupted by an insulating barrier, or by the breaking of a rail, the abutting ends of which are separated, will indicate such condition at a signal controlled by the particular block in which this accident has taken place. In the present instance, the interruption of the circuit by the insulating members 12 has been intentional and the electric current is carried across this insulating barrier by signal wires 13 and 14, one terminal of each of these wires being connected to a rail, as indicated at 15. The opposite terminal is connected to the continuation of this rail on the opposite side of the insulating joint, as indicated at 16. This insulated joint occurs near the end of a structure, such as a bridge, or trestle, and the length of the wires 13 and 14 are designed to be sufficient to form a loop back and forth across the structure. In the present instance each wire will form parallel lengths which may be led across the structure in any manner desired, although here shown as supported upon the cross ties of the trestle. Interruption of the wire at any point along its length will have the same effect as breaking one of the main rails, or other conditions which would cause the approximate block signal to indicate danger.

The signal wires 13 and 14 are composed of short lengths of wire 17, as particularly indicated in Fig. 3. These lengths are upset at their ends to provide a flared portion 18. The adjacent flared ends are embedded within fusible couplings 19. Attention is directed to the fact that the ends of these wires are held substantially in contact by the fusible connection and that a minimum amount of the fusible material will be present between the adjacent ends of the sections. Due to the manner in which the ends of these sections are upset the fusible material will hold the sections in their joined positions and will resist a considerable tension strain. It will be understood that the material forming the joints 19 is sensitive to heat and will melt under excess heat to liberate the ends of the sections, thus causing the wires to be broken and the flow of electricity therethrough to be discontinued.

In the operation of the present invention the railway rails are interrupted at joints near a bridge or trestle by an insulating barrier 12, after which the ends of wires 13 and 14 are secured to the adjacent ends of the rails upon opposite sides of the insulation. These wires may then be looped across the trestle structure in any manner desired, it being understood that the wires 10 have first been assembled, as indicated in Fig. 3. Under normal conditions the presence of the wires 13 and 14 in the block signal rail circuits will be of no consequence, as the circuit through the rails will 15 not be interrupted but will be caused to make a detour around the insulating joints 12 and through the wires 13 and 14. In the event that the bridge burns, or is otherwise torn away, the wires 13 and 14 will 20 be broken, either by heat which would melt the fusible joints, or by excess of tension which would pull some of the joints apart.

It will thus be seen that by the simple expedient here shown it is possible to provide 25 desirable signal means for use in connection with the usual railway block signal system to indicate danger at a trestle, bridge, or other similar structure, which danger might be brought about by fire, flood, or like disaster.

While I have shown the preferred form 30 of my invention, it is to be understood that various changes might be made by those skilled in the art without departing from the spirit of my invention.

Having thus described my invention, what I claim and desire to secure by Letters Patent is:

1. In combination with a railway block

system in which electric currents are carried through the track rails, said track extending across a supporting structure; means insulating the contiguous ends of rails of the track at a point near said supporting structure; and a signal wire adapted 40 to be broken by accident to the structure, which wire is looped across the supporting structure, and has its terminal ends secured to the contiguous ends of the rails on the opposite sides of the insulated joint. 50

2. In combination with a railway block system in which electric currents are carried through the track rails, said track extending across a supporting structure; means insulating the contiguous ends of rails of the track at a point near said supporting structure; a signal wire formed by a plurality of 55 connected sections adapted to be separated by excessive tension or by excessive heat, said signal wire being looped across the supporting structure and being secured by its terminal ends to the adjacent rails upon the opposite sides of the insulated joint.

3. In combination with a railway block system in which electric circuits are carried 60 by track rails, said rails extending across a supporting structure, means insulating contiguous ends of the rails near one end of the supporting structure, a fusible wire secured to the ends of the contiguous rails 70 at opposite sides of said insulating means, said wire extending from one fastening point across the supporting structure and returning across the supporting structure to the fastening point upon the opposite side 75 of the insulating barrier.

WILLIAM P. GREGORY.
